UNITED STATES PATENT OFFICE.

LOUIS H. ROCKAFELLOW, OF SEATTLE, WASHINGTON, ASSIGNOR OF ONE-HALF TO
CHARLES C. DOSE, OF KING COUNTY, WASHINGTON.

Fixture-Lamp.

1,208,017.

Specification of Letters Patent. Patented Dec. 12, 1916.

Application filed December 6, 1915. Serial No. 65,340.

To all whom it may concern:

Be it known that I, Louis H. Rockafellow, a citizen of the United States, and a resident of Seattle, in the county of King and State of Washington, have invented certain new and useful Improvements in Fixture-Lamps, of which the following is a full, true, and exact specification.

My invention relates to improvements in fixture lamps and has for its principal object to provide an improved and novel form of fixture in which an improved reflector is utilized to concentrate a portion of the light rays at a predetermined point; to provide means whereby the reflector may be adjusted with respect to the source of light; to provide a novel form of multiple reflector.

Other objects will appear as my invention is more fully explained in the following specification, illustrated in the accompanying drawings and pointed out in the appended claim.

In the drawings Figure 1 is a side elevation of my improved fixture with parts broken away along a central line. Fig. 2 is a bottom plan view showing the reflector in particular.

Referring more particularly to the drawings, numeral 1 indicates an electric bulb socket of the usual type, which is secured to a ceiling yoke 2 which in turn is fastened to a ceiling 3. A circular plate or spider 4 having a central opening which fits slidably over socket 1, is adjustably held in place by screws 5, which screw into yoke 2. By means of the screws 5, the spider 4 may be raised or lowered within certain limits. Secured to spider 4 is a concave reflector backing 6 upon the inner face of which are mounted a plurality of plane reflectors 7. The reflectors are arranged in circles and at such angles with respect to a source of light 8 that the light rays emanating from said source which strike the reflectors centrally, are reflected convergently toward a common center which will be on the axis of the fixture. The reflectors 7 are held to the backing 6 by means of clips 9 which may be integral

with or stamped out from the backing member and are bent over the edges or corners of the reflectors 7.

As previously stated the reflectors may be raised or lowered with respect to the source of light by means of the screws 5. The changing of the position of the reflectors will alter the focal point of the central rays as reflected. An ornamental shell 10 is secured to spider 4 by means of screw rods 11. A globe 12 is supported from the shell in the usual manner.

The concave and multiple reflector reflects and concentrates the light, which is originally thrown upwardly, toward a point directly beneath the light fixture whereby a light of great intensity is produced.

While I have shown a particular form of embodiment of my invention, I am aware that many minor changes therein will readily suggest themselves to others skilled in the art without departing from the spirit and scope of the invention, and I therefore desire to avoid being limited to the exact form shown and described except as pointed out in the appended claim.

Having described my invention, what I claim as new and desire to protect by Letters Patent, is—

In a device of the class described, including a lamp bulb and a lamp socket which is attached to a ceiling yoke, the combination of a spider located centrally with respect to the said receptacle and adjustably secured to the said yoke, a concave reflector backing concentric with said spider and secured thereto, a plurality of trapezoidal reflecting surfaces arranged in circular and radial rows upon and secured to the inner face of the said reflector backing and at such angles with respect to a common point in the said light bulb that the rays of light which emanate from said point and strike said reflecting surfaces centrally will be reflected toward a common focal point located on the axis of the light bulb and at a predetermined distance from said common source point.

LOUIS H. ROCKAFELLOW.
